UNITED STATES PATENT OFFICE.

GEORGE HAAG, OF PEORIA, ILLINOIS.

COMBINED CLUTCH AND LATCH MECHANISM.

Application filed April 14, 1924. Serial No. 706,286.

To all whom it may concern:

Be it known that GEORGE HAAG, a citizen of the United States of America, residing at Peoria, Illinois, in the county of Peoria and State of Illinois, has invented certain new and useful Improvements in a Combined Clutch and Latch Mechanism, of which the following is a specification.

My invention relates to power operated washing machines, and more particularly to a specific clutch and latching mechanism for the tub portion.

The object of my invention is in the provision of a special clutching mechanism for the tub portion of a power washing machine, said clutching mechanism having means operating therewith to locate said tub portion in a set position when desired.

Another object of my invention is in the provision of a combined latch and clutch mechanism for controlling the movement of the tub portion of a power washing machine.

A further object of my invention is in the provision of a special latch means operating simultaneously with the clutching mechanism to permit latching of the tub portion of the washer only when said tub is in a non-clutched relation with the drive mechanism.

A still further object of my invention is in the provision of a special latch mechanism for the tub portion of a power washer, said latch portion operating simultaneously with the clutch lever, not only to hold it in either of its operative positions but also acting additionally to position the tub fixedly when desired.

Other objects of my invention will appear in the following specification, taken in connection with the annexed drawings in which:

Figure 1 is an end elevation of a power washing machine.

Figure 2 is a sectional view taken on the line 2—2 of Figure 3.

Figure 3 is a partial plan view from above of the combined clutch and latch mechanism showing their mounting on the washer.

Figure 4 is a longitudinal sectional view showing in detail the operating portions of the clutch and latch mechanism, and,

Figure 5 is an end elevation of the tub portion.

Referring to the drawings I have shown a power operated washing machine of the oscillating type, said machine having the frame portion described generally as 10, with a supporting means 11 thereunder, upon which the drive mechanism shown but generally, is located. A conventional electric motor 12 drives through related gears the crank arm 13, said crank arm 13 operating the lever 14 which is pivoted thereto as at 15. The upper end of the lever 14 is pivoted at 16 to a short arm 17 which has for its base portion the plate 17^a which provides the male clutch portion to be later described. A hub portion 18 has formed thereupon an outwardly projecting lug 20 adapted to engage a corresponding slideway 21 formed in the bracket 22 which is positively attached by means of numerous bolt members to the tub 19. A lug 23 limits the movement of the portion 20 in the slide way 21 and locate same with relation to the axis of the tub. An arm 24 integrally cast with the hub 18, has attached thereto in a pivotal manner, a bolt 23^a. A coil spring 26 is fastened to the outer end of the bolt, said spring engaging in a similar manner another bolt 27 pivoted at 28 in the frame of the washer.

Referring again to the bracket 22 on the tub portion, attention is called to the recesses 29 and 30 formed therein adjacent the top of the tub. The hub 18 projects as shown in Figure 4 through the side of the machine, said hub having as its axis the shaft 31 which is supported at its outer end in a bracket 32 which is fixedly attached to the frame and side portion 33 of the washer. The stub shaft 31 is pinned to the bracket 32 as at 34. This bracket 32 provides also the supporting portions for the clutch mechanism now to be described.

The plate 17^a which forms the male clutch portion provides a bearing for the hub 18 and is slidable thereon, said clutch portion 17^a being adapted upon the proper movement to engage the female portions 35 in the lug 20. Means for moving the clutch portion 17^a into and out of engagement with

the lug 20 is provided in a cam operated mechanism including a tooth 36 engaging a corresponding groove 36^a on the clutch portion 17^a said tooth having an eccentric 5 mounting upon a rotatable member 37. Means for rotating the member 37 is provided in the vertically positioned shaft 38 and lever 39 connected to its upper end. A plate 40 engages the frame portion of the 10 washer as at 41 and provides a bearing surface for the lever 39. The plate 40 is recessed at 41^a as well as at a point 42 adjacent the tub or rather adjacent the recesses 29 and 30 which are fashioned in the bracket 15 22 on the side of said tub. A latch 43 is pivoted at 44 in the hub portion 45 of the lever 39 with the result that movement of said lever imparts to said latch a corresponding movement.

20 The operation of my combined clutch and latch mechanism is as follows:

The operation of washing clothes necessitates of course the stopping of the tub portion during the times when the clothes 25 are placed therein and also when they are to be withdrawn. Means for connecting the drive mechanism and the tub portion is provided in the clutch mechanism including the male portion 17^a and the female portion 35. 30 Means for driving the tub portion is provided in the motor 12 and conventional lever connections which finally engage the arm 17 which is pivotally engaged to the male portion 17^a of the clutch, hence, with the clutch portion 17^a engaging the opposed clutch face 35 movement will be transmitted to the tub portion and with a disengagement of the clutch portions the oscillatory movement of the tub ceases.

40 Means for throwing into and out of engagement the clutch mechanism is provided as heretofore described in the eccentric mounting controlled by a hand lever 39. Inasmuch as the latch 43 is pivoted upon 45 the hub portion of said hand lever and rotates therewith, in order to move said lever 39 it is necessary to depress the inner end 46 of the latch in order to withdraw the operative end from engagement with one of the recesses 29 or 30 on the tub.

50 In Figure 3 of the drawings the clutch operating hand lever 39 is shown in the idle position, that is with the clutch disengaged and the latch 43 engaging the recess 29 in the tub, thus holding the tub stationary. It may be seen however that should the inner end of the latch be depressed and the hand lever moved to a position on the plate parallel to the shaft 31, 55 that the clutch portion 17^a would engage the female portion 35 thereby transmitting movement to the tub, said tub having been released by the latch upon the first movement of the lever 39.

Referring again to Figure 3, attention 65 is called to the notch 41^a in plate 40 said notch receiving the pivoted latch 43 when the clutch lever is thrown to its clutched position. The above positive location of the lever prevents accidental disengagement 70 of the clutch without the act of first releasing the latch member.

The above structure, the operation of which has been described was developed for the purpose of locating the tub portion in 75 an immovable position and at the same time insuring against any danger of movement thereof through some accidental clutch movement. As a matter of fact, the actual clutch shown in the present application is 80 old in the art and the structure here shown is directed to the combined clutch operating mechanism and latch whereby positioning of the tub in a fixed position is only possible when the clutch is disengaged. Likewise 85 with the clutch mechanism in its operative position the latch member engages the recess 41^a on the plate 40 to prevent any movement accidental or otherwise of the clutch operating lever 39 without first releasing 90 said latch.

The two notches 29, and 30, are provided for optional placement of the tub either in a vertical position or a slightly tilted position. The reason for same being that the 95 operator may be standing upon one side of the tub and therefore, with the latch in notch 30, would have better access thereto, for the wringing operation, to permit movement of the tub to either one of the positions. Releasing of the latch 43 is, of course, necessary with a consequent manual movement of the tub against the tension of the springs. It is obvious, of course, 100 that a plurality of notches for locating the tub in any desired position, might be used.

105 What I claim is:

1. In a device of the class described, in combination, a reversibly moving tub member, power means for operating said tub, clutch mechanism providing optional engagement of the tub and power mechanism, a hand lever adapted to operate said clutch mechanism and a latch member pivoted on said hand lever and adapted to locate the 110 tub portion in a fixed position when said hand lever is in a non-clutched position as well as lock the hand lever against accidental movement.

115 2. In a device of the class described, in combination, a reversibly moving tub portion, driving means therefor, clutch means providing optional engagement between the tub and drive portions, a hand lever controlling the operation of said clutch mechanism and a latch member movable with said hand lever and adapted when said hand lever is in its non-clutched position, to locate the 120 125

tub portion in a fixed manner as well as lock the hand lever against accidental movement.

3. In a device of the class described, in combination, a reversible tub member, power means for operating said tub, clutch mechanism between the tub and power operating means, a hand lever adapted to

move said clutch mechanism into an operative or inoperative position and a latch member operating simultaneously with said hand lever to hold the latter against accidental movement when the clutch is in either operative or inoperative position. ¹⁰

In testimony whereof I affix my signature.

GEORGE HAAG.
